UNITED STATES PATENT OFFICE.

HENRY C. MAXWELL, OF ROME, NEW YORK.

BREECHING-RING FOR HARNESS.

SPECIFICATION forming part of Letters Patent No. 366,495, dated July 12, 1887.

Application filed April 14, 1887. Serial No. 231,848. (No model.)

To all whom it may concern:

Be it known that I, HENRY C. MAXWELL, a citizen of the United States, residing at Rome, in the county of Oneida and State of New York, 5 have invented certain new and useful Improvements in Breeching-Rings; and I do hereby declare the following to be a full, clear, and exact description of the invention, such as will enable others skilled in the art to which it appertains to make and use the same.

This invention relates to improvements on Patent No. 305,458, granted to me on the 23d day of September, 1884, in harness-trimmings for breeching-rings; and it consists in the 15 novel construction of the same, whereby the brace of a hip-strap is prevented from coming in contact with the end of the breeching, all as will be hereinafter explained.

The annexed drawing, to which reference is 20 made, illustrates my invention, in which the figure represents a side view of my device having part of the breeching and hip strap stay or brace attached.

Referring by letter to the annexed drawing, 25 A designates a breeching-ring, to which is attached the end of a breeching to its vertical bar *a*, and a hip-strap brace, *b*, to the upper horizontal portion thereof. This ring is provided with a guard, *c*, which is cast integral 30 therewith, forming a loop for the end of the breeching, which loop consists of the horizontal bar *e* and vertical bar *f*, in connection

with the bar *a* of the ring, which separates the breeching from the stay, which latter lies in the space *d*, formed above the guard and below the upper horizontal bar of the ring. 35

It will be seen that the guard is provided within the open space of the ring, and that the breeching and stay are prevented from coming in contact with one another, and it is ornamental and cheap to manufacture. 40

I am aware that patents numbered 341,717 and 229,166 were granted, and do not claim such construction shown in either patent; but, 45

Having described my invention, what I claim is—

As an improved article of manufacture, the within-described breeching-ring, consisting of the ring proper and elongated loop formed 50 integral, said loop arranged within the ring and adjacent to the vertical bar to which the breeching is secured, said loop extending nearly to the upper horizontal bar of the ring, and forming the space *d* between said bar and 55 the bar *e* for the end of the brace *b*, as shown and described.

In testimony whereof I affix my signature in presence of two witnesses.

HENRY C. MAXWELL.
